Claims priority, application Great Britain Nov. 18, 1968

Term of patent 14 years

Int. Cl. D9—02

U.S. Cl. D9—254

Fig. 1.

Fig. 2.

Fig. 3.

FIG. 1 is a top plan view of a cover for a tray for food showing my new design;

FIG. 2 is a sectional view thereof taken on line 2—2 of FIG. 1; and

FIG. 3 is a sectional view thereof taken on line 3—3 of FIG. 1.

The essential features of my design reside in the proportions of the sides of the rectangular tray cover as a whole, the proportions of the asymmetrically placed rectangular depression in the cover, and in the relationships between the proportions of the depression and the cover as a whole.

I claim:

The ornamental design for a cover for a tray for food, as shown and described.
